United States Patent Office

Des. 198,247
Patented May 19, 1964

198,247

BALLOON

Paul K. Kindling, Wadsworth, Ohio, assignor to Goodyear
Aircraft Corporation, Akron, Ohio, a corporation of
Delaware

Filed June 28, 1963, Ser. No. 75,583

Term of patent 14 years

(Cl. D71—1)

FIG.-1

FIG.-2

Des. 198,247

PAGE 2

FIG. 1 is a top perspective view of a balloon showing my new design with the broken line portions omitted for convenience of illustration;

FIG. 2 is a bottom perspective view;

FIG. 3 is a top plan view;

FIG. 4 is a side elevational view; and

FIG. 5 is a rear elevational view.

The essential features of my design reside in the portion shown in full lines in the drawings.

I claim:

The ornamental design for a balloon, as shown and described.
